CLAIM

The ornamental design for an absorbent article substrate with a pattern, as shown and described.

DESCRIPTION

FIG. 1 is a perspective view of an absorbent article substrate with a pattern;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dashed broken lines illustrating the sides and rear and the areas surrounding the central shapes formed by ovular elements visible in FIGS. 1 and 2 depict environmental subject matter that forms no part of the claimed design.
